UNITED STATES PATENT OFFICE.

FREDERICK H. MILLER, OF PORTLAND, OREGON.

VEGETABLE CUTTER.

Application filed August 13, 1926. Serial No. 129,017.

The invention generally relates to vegetable cutters and more particularly to that class of such devices which is adaptable to use for slicing potatoes, for "shoe string" or 5 "French" fries.

The invention primarily seeks to provide a hand operated vegetable cutter of the class stated which is simple and economically constructed and efficient in its operation of cutting potatoes as stated, and in which means is provided for adapting the device for cutting the potatoes in the various manners desired, for overcoming tendency of the potatoes to "stick" to the cutting element, and 10 for so holding the potato or other vegetable being cut as to automatically effect a feeding thereof to the cutting elements without danger to the operator of cutting his hands on said cutting elements.

With the above and other objects in view that will hereinafter appear, the invention further resides in the novel details of construction, combination and arrangement of parts, all of which will be first fully described, then be particularly pointed out in the appended claims, reference being had to the accompanying drawings, in which:

Figure 1 is a perspective view of the invention.

Figure 2 is a plan view.

Figure 3 is a central vertical longitudinal section of the invention.

Figures 4 and 5 are vertical cross sections taken on the lines 4-4 and 5-5 respectively on Figure 3.

Figure 6 is a perspective view of the "shoe string" cutter unit.

Figure 7 is a perspective view of the "French fry" cutter unit.

Figure 8 is a perspective view of the replacement table used when slicing vegetables.

Figure 9 is a detail longitudinal section illustrating the "French fry" cutter unit mounted for use.

In the drawings, in which like numerals of reference indicate like parts in all of the figures, 1 represents the base frame having extending flanges 2 for supporting the base upon a suitable support and the said base 1 is provided along each lateral edge with a plurality of upstanding lugs 3, each lateral series of lugs being adapted to support a guide rail 4, the said guide rails being disposed in parallel relation and on a common plane.

The side rails 4 are secured upon the lugs as at 5.

The base frame 1 includes a cross bridge portion 6 in one end thereof and a second cross bridge portion 7 intermediately of the ends thereof, both said bridge portions being longitudinally slotted as at 8 to receive the securing bolts 9 which pass therethrough and through the respective ends of the knife member 10 provided at its advance end with a horizontal knife edge 11.

The bridge portion 7 is provided with a pair of tapped lugs 12 adapted to receive the set screws 13 which pass upwardly through the said lugs and engage the underside of the advance end of the knife member 10.

Except for longitudinal adjustments permitted by the slots 8 that end of the knife member 10 which is bolted to the cross bridge portion 6 is relatively permanently secured, while the other end of the said knife member against which the set screws 13 project, is adapted to be vertically adjustable. By loosening up on the bolts 9 passing through that end of the knife member and screwing the set screw 13 upwardly the advance knife edge 11 may be moved upwardly to a desired adjustment. The reverse action of the bolts and set screws will provide for a downward movement of the said knife edge, thus making it possible to vary the elevation of the said horizontal knife edge above the top surface of the base frame 1.

A vertical slicer unit 14 is provided and is secured to the base frame as at 15 in advance of the horizontal knife edge 11. The unit 14 is in the nature of a hollow box-like casing adapted to house a plurality of spacer plates 16 and between each adjacent pair of spacer plates is mounted a razor blade 17, the said spacer plates and blades being clamped to position by the clamp screws 18 which pass through one end of the box-like housing and engage the nearest plate and which screws are accessible through holes 19 provided in one side flange 2 of the base frame.

In advance of the position of the slicer unit the base frame is provided with a table surface 20 which, it will be noticed, is in the nature of a depression and is on a lower level than the top surface of the box-like casing of the slicer unit and is hereinafter termed the low table face.

A plate 21 is secured to the base frame immediately above the table face 20 as at 22,

the top surface of the said plate being flush with the top surface of the box-like casing of the slicer unit.

It is to be understood that my improved vegetable cutter is adaptable for a three-fold purpose of slicing up potatoes for "shoe string fries," for "French fries" or for the ordinary slices used in making "German or pan fries" or "Saratoga chips."

When it is desired to slice potatoes for the first mentioned type of fries, namely,—"shoe string," the slicer unit 14 is used and mounted as illustrated in Figure 3 of the drawings, the blades 17 being positioned as illustrated in Figure 6 with relatively narrow spaces therebetween and the knife edge 11 adjusted accordingly.

When it is desired to utilize the invention for slicing French fries, the plate 21 is removed and the low table face 20 is brought into use. In this case, the slicer unit 23 illustrated in Figure 7 is mounted in place in the unit 14 hereinbefore described. It will be observed that the unit 23 has its blades spaced much wider apart than those of the first mentioned unit and when this unit is used the knife edge 11 is adjusted to a suitable corresponding elevation. It will also be observed that the securing lugs by which the unit 23 is secured to the base frame as at 15 are so positioned that the top surface of the unit will be positioned flush with the low table face 20.

Obviously as a potato is moved across the top surface of the plate 21 on the table face 20, as the case may be, and across the slicer unit 14 or 23, as the case may be, the vertical blades 17 of the slicer unit will cut equidistantly spaced vertical kerfs in the lower portion of the potato. On continued movement the potato is brought into engagement with the transverse knife edge 11 when the said knife edge will traverse the kerfs cut by the blades 17 and sever the lower portion of the potato into a plurality of long slices substantially square in cross section and adaptable for use in making "shoe string" or "French fries", according to which of the slicer units is employed.

If it is desired to simply slice the potato for use in making "German fries" or "Saratoga chips", the plate 21 which forms the upper table face is mounted and the solid plate 24 is used as a replacement for the slicer unit 23. This plate is illustrated in Figure 8 and the mounting lugs of the said plate are so positioned that when mounted the upper flat face of the plate will be positioned on a plate on a plane flush with that of the plate 21 so that when a potato is moved over the plate 24 no vertical kerfs will be cut therein as when the slicer units are used but a horizontal slice only will be effected when the said potato is brought into

engagement with the properly adjusted 65 transverse knife edge 11.

In the use of devices of this type much difficulty is occasioned in feeding the potatoes to the cutting elements and much danger of cutting the hands of the operator 70 is also present. In my present invention I provide means which, while actuated by hand operation, serves automatically to feed the potatoes to the cutting elements in a manner assuring proper cutting, and slicing 75 thereof without danger whatever to the operator.

To accomplish this last stated purpose I provide end frames 25 and 26 each having an extended hub at each lateral side thereof 80 adapted to receive one end of a guide rod 27, the guide rod being secured in the said hubs as at 29. Each of the frames 25 and 26 also includes at each lateral side thereof a guide foot 30 adapted to ride on and be 85 guided by the rails 4. One of the frames has secured thereto as at 31 a block 32 having an upstanding handle portion 33 and a vegetable receiving half groove 34.

Another frame 35 is provided intermediately of the frames 25 and 26 and has secured thereto as at 36 a block 37 which, like the block 32, is equipped with a vegetable receiving half groove 38. The frame 35 is also provided with an upstanding handle 95 portion 39 and laterally extended guide lugs 40 slidably guided upon the rods 27.

Springs 28 are mounted on the guide rods 27 between the guide lugs of the end frame 26 and those of the frame 35, the said 100 springs always tending to force the blocks 32 and 37 together.

It will be observed by reference to Figures 3 and 9 that the half grooves 34 and 38 have their opposed faces cut on an angle so as to 105 converge upwardly and diverge downwardly. Thus, when a potato or other vegetable is mounted between the blocks in the half grooves, the springs, tending to force the blocks together, and the diverging walls of 110 the half grooves, will co-act to automatically force the said potato or other vegetable into engagement with the cutting elements. In this manner it is unnecessary for the attendant to force the vegetables with his hand and 115 all danger of injury during the cutting and slicing operation is thereby overcome.

It will be observed that by mounting the knife member 10, as illustrated and described, the upper surface of that knife member presented to the potato or other vegetable passing thereover is positioned on a downward incline from the knife edge 11 toward the rear end of the device. This incline serves to permit entrance of air between the potato being cut and the upper surface of the knife member, and suction such as would cause the potato to cling to

the upper surface of the knife member is thus effectively overcome. This incline of the knife member also serves to hold the vegetable being cut down into engagement 5 with the cutting element.

In the foregoing description, I have disclosed a simple and efficiently operable device for cutting potatoes for use in making "shoe string fries", "French fries", "German fries" 10 or "Saratoga chips", and also for slicing vegetables, means also being provided for effecting the operations stated without danger to the operator from the cutting act, the feeding of the vegetables to the cutting elements 15 being accomplished automatically and from this description, taken together with the accompanying drawing, it is thought that the novel details of construction, manner of operation of the invention and the 20 advantages thereof will be readily apparent to those skilled in the art to which it appertains.

What I claim is:

1. In vegetable cutters of the character 25 described, a base frame including a bed, a cutting mechanism carried by the bed, slide rails mounted on the base frame above the bed, a vegetable holding carriage operatively mounted on the slide rails and comprising means continuously tending to feed the vegetable downwardly toward the base to be engaged by the cutting mechanism, said last named means comprising a sectional holding block having inclined walls and yieldable 30 means for forcing said blocks toward each other with the vegetable between them.

2. In vegetable cutters of the character 40 described, a base frame, a bed including an elongated approximately horizontal plate having a cutting edge at one end, means for securing the other end of said plate to the base frame, means for adjustably securing that end of the plate having the cutting edge to the base frame whereby the plate may be 45 inclined to the horizontal at different angles, said bed also including a non-adjustable plate, said adjustable plate and said non-adjustable plate being spaced apart, and a holder unit with a gang of vertical knives located 50 in the base frame between the adjacent ends of said plates for the purposes specified.

3. In vegetable cutters of the character 55 described, a base frame, a bed including an elongated approximately horizontal plate having a cutting edge at one end, means for securing the other end of said plate to the base frame, means for adjustably securing that end of the plate having the cutting edge to the base frame whereby the plate may be 60 inclined to the horizontal at different angles, said bed also including a non-adjustable plate, said adjustable plate and said non-adjustable plate being spaced apart, and a body secured to the base frame in the space between 65 said plates for the purposes specified.

4. In vegetable cutters of the character described, a base frame including a bed, a cutting mechanism carried by the bed, slide rails mounted on the base frame above the bed, a vegetable holding carriage operatively 70 mounted on the slide rails and comprising means continuously tending to feed the vegetable downwardly toward the base to be engaged by the cutting mechanism, said last named means comprising a pair of blocks 75 and yieldable means for forcing the blocks toward each other with the vegetable between them, said blocks having opposed vegetable receiving grooves, said grooves having downwardly diverging walls. 80

5. In vegetable cutters of the character described, a base frame including a bed, a cutting mechanism carried by the bed, slide rails mounted on the base frame above the bed, a vegetable holding carriage operatively 85 mounted on the slide rails and comprising means continuously tending to feed the vegetable downwardly toward the base to be engaged by the cutting mechanism, said last named means comprising a fixed block, a 90 movable block, and means always tending to force the movable block against the fixed block, said blocks each having a half-groove in opposition to that of the other block whereby to cooperatively provide a vegetable 95 receiving pocket between the blocks, said half-groove being downwardly inclined whereby to provide downwardly diverging walls for said pocket for the purposes specified. 100

6. In vegetable cutters of the character described, a base frame including a bed, a cutting mechanism carried by the bed, slide rails mounted on the base frame above the bed, a vegetable holding carriage operatively 105 mounted on the slide rails and comprising means continuously tending to feed the vegetable downwardly toward the base to be engaged by the cutting mechanism, said carriage comprising a pair of end frames each 110 having lateral feet adapted to be guided by the slide rails and laterally extended hubs, guide rods secured in the hubs and holding the frames in opposed spaced relation, an intermediate frame having laterally extended hubs slide guided on the guide rods, and said vegetable feeding means comprising 115 a fixed block carried by one end frame, a movable block carried by said intermediate frame, said blocks each having a half-groove 120 in opposition to that of the other block whereby to cooperatively provide a vegetable receiving pocket between the blocks, said half-grooves being downwardly inclined whereby to provide downwardly diverging walls for said pocket, and springs interposed 125 between the intermediate frame and the other end frame always tending to force the movable block against the fixed block.

FREDERICK H. MILLER.
